UNITED STATES PATENT OFFICE.

ARTHUR SCHOENBRUN, OF NEW YORK, N. Y., ASSIGNOR TO MAGNUM IMPORT CO., INC.,
OF NEW YORK, N. Y.

DESIGN FOR A STOPPERED LIQUID CONTAINER.

Application filed May 27, 1922. Serial No. 2,437. Term of patent 7 years.

To all whom it may concern:

Be it known that I, ARTHUR SCHOENBRUN, a citizen of the United States, residing at New York city, in the county and State of New York, have invented a new, original, and ornamental Design for a Stoppered Liquid Container, of which the following is a specification, reference being had to the accompanying drawing, forming part thereof.

Figure 1 is a front elevational view of a stoppered liquid container;

Figure 2 is an edge elevational view thereof.

I claim:

The ornamental design for a stoppered liquid container, as shown.

ARTHUR SCHOENBRUN.

Witnesses:

CLARICE FRANCK,
RAYMOND RICHARDSON.
